UNITED STATES PATENT OFFICE.

MADELEINE T. RAYNOLDS, OF NEW YORK, N. Y.

DESIGN FOR A COMBINED SALT AND PEPPER CARRIER.

45,728.

Specification for Design.

Patented May 5, 1914.

Application filed January 15, 1914. Serial No. 812,353. Term of patent 3½ years.

To all whom it may concern:

Be it known that I, MADELEINE T. RAYNOLDS, a citizen of the United States, residing in the borough of Manhattan, city, county, and State of New York, have invented a new, original, and ornamental Design for a Combined Salt and Pepper Carrier for Table Use, of which the following is a specification, reference being had to the accompanying drawing, forming part hereof.

Figure 1 is a plan view and Fig. 2 is an elevation of a combined salt and papper carrier showing my new design.

I claim:

The ornamental design for a combined salt and pepper carrier, as shown.

MADELEINE T. RAYNOLDS.

Witnesses:

PHILLIPS ABBOTT,

EDWIN F. VALENTINE.
